(57) **CLAIM**

The ornamental design for a lamp housing, battery housing, and solar panel for a solar light fixture, as shown and described.

DESCRIPTION

FIG. 1 is a rear side perspective view of the lamp housing, battery housing, and solar panel for a solar light fixture; FIG. 2 is a front side perspective view of the lamp housing, battery housing, and solar panel for a solar light fixture; FIG. 3 is a front elevation view of the lamp housing, battery housing, and solar panel for a solar light fixture; FIG. 4 is a rear elevation view of the lamp housing, battery housing, and solar panel for a solar light fixture; FIG. 5 is a top plan view of the lamp housing, battery housing, and solar panel for a solar light fixture; FIG. 6 is a bottom plan view of the lamp housing, battery housing, and solar panel for a solar light fixture; FIG. 7 is a left side elevation view of the lamp housing, battery housing, and solar panel for a solar light fixture; and, FIG. 8 is a right side elevation view of the lamp housing, battery housing, and solar panel for a solar light fixture. The broken lines shown represent unclaimed subject matter and form no part of the claimed design. The unclaimed portion of the pole for the solar light fixture has been shown as broken in a middle portion to indicate indeterminate length.

1 Claim, 8 Drawing Sheets
